UNITED STATES PATENT OFFICE.

WILLIAM E. WOODARD, OF FOREST HILLS, AND FREDERICK W. MARTIN, OF BROOKLYN, NEW YORK, ASSIGNEES TO FRANKLIN RAILWAY SUPPLY COMPANY, A CORPORATION OF DELAWARE.

DRIVING-BOX WEDGE ADJUSTMENT.

Application filed October 4, 1921. Serial No. 505,304.

To all whom it may concern:

Be it known that we, WILLIAM E. WOODARD and FREDERICK W. MARTIN, both citizens of the United States, residing at Forest Hills, in the county of Queens and State of New York, and Brooklyn, in the county of Kings and State of New York, respectively, have invented certain new and useful Improvements in Driving-Box Wedge Adjustments, of which the following is a specification.

Our invention relates to driving box wedge adjustment where automatic wear compensating wedges are used, as on locomotives. We aim to make the adjustment of the compensating devices or mechanism easy and convenient; to make the mechanism simple, durable, rugged, and proof against dangerous maladjustment; and to afford plain, definite indications of when, on the one hand, the cumulation of wear is so great as to require readjustment, and of when, on the other hand, the preferable readjustment has been made.

How these and other advantages can be secured through our invention will appear from our description hereinafter of the best embodiments of the invention known to us.

In the drawings, Fig. 1 shows a steam locomotive driving box with provision for adjustment according to our invention. The box proper and the compensating wedges are here shown in transverse section, while the adjusting mechanism proper, the pedestal jaws of the locomotive frame, and the pedestal binder are shown in elevation.

Fig. 2 shows an axial mid section through the adjusting mechanism, on a larger scale than Fig. 1, taken as indicated by the line 2-2 in Fig. 4.

Fig. 3 shows an axial mid section at right angles to Fig. 2, taken as indicated by the line 3-3 in Fig. 2.

Fig. 4 is a plan view of the adjusting mechanism.

Figs. 5, 6 and 7 are detached views of parts of the adjusting mechanism on a scale larger than that of Fig. 1 but smaller than that of Figs. 2, 3 and 4.—Fig. 5 being a perspective view of one part, and Figs. 6 and 7 being a side elevation and an inverted plan view, respectively, of another part.

Figs. 8 and 9 show a somewhat different

form of adjusting mechanism,—Fig. 8 showing a section corresponding to Fig. 2 taken as indicated by the line 8-8 in Fig. 9, and Fig. 9 being a plan view.

Figs. 10 and 11 show a further modification,—Fig. 10 being a side elevation with a part omitted, and Fig. 11 showing a cross section taken as indicated by the line 11-11 in Fig. 10.

The locomotive frame 13 in Fig. 1 has the usual pedestal jaws 14, 15 wherein is mounted for vertical play the driving box 16, with gibbs 17, 18 on its pedestal faces. The frame 13 has also the usual pedestal binder 19. Between the driving box gib 18 and the adjacent pedestal jaw 15 (which has an inclined face) are interposed two wedges 20, 21 which afford automatic compensation for wear of the driving box and the pedestal jaws,—in a manner well understood in the art. The main wedge 20 is attached to one end of a rod or bolt 22 that extends down through an opening in the pedestal binder 19. This wedge 20 is automatically and yieldingly pressed home by mechanism of our invention, collectively indicated at 25. Not only does the mechanism 25 serve in the automatic adjustment of the compensating device 20, 21, but it is itself adjustable to assure proper action of said device.

Referring, now to Figs. 1 to 7 generally, it will be seen that the mechanism 25 by which the wedge 20 is actuated comprises a helical compression spring 26 acting through a cap-like nut 27 threaded on the bolt 22. As shown, the upper end of the spring 26 is seated and engaged in an annular groove or recess 28 in the lower side of the cap nut 27, while the lower end of said spring is seated and engaged in the bottom of a hollow cup-like member 30, which thus serves as a support or abutment for the spring. Surrounding the bolt 22 within the spring 26 is an auxiliary helical compression spring 31 (smaller and less powerful than the spring 26) which is seated and acts on the inner wall of the groove 28 at its upper end and on the bottom of a shallow depression 33 in the bottom of the cup member 30 at its lower end. In order that rotation of the member 30 may produce relative rotation as between bolt 22 and nut 27 and thus alter the vertical position of the nut and the adjustment of the mecha-

nism 25, free-sliding anti-turning engagement between the parts 30 and 27 is provided for. As shown, the cup 30 has diametrically opposite vertical slots 35 wherein 5 are engaged corresponding lugs 36 on the cap 27, so that rotation of the cup one way or the other will turn the cap and thus screw it up or down on the bolt 22 and vary the compression or initial "tension" of the 10 springs 26 and 31. As shown, the member 30 bears and is supported on the bottom of a U-shaped yoke or bracket 37 whose upper ends are secured to the lower side of the pedestal binder 19 by bolts 38, and the reduced 15 lower portion 40 of said member 30 projects below the bracket and is squared at 41 to afford a convenient hold for a wrench.

Referring, now, more especially to Figs. 1, 2, 3, 5 and 6, it will be observed that in the upper edge of the cup member 30 are wide but shallow depressions 42, and that the top of the cap or nut member 27 is cut away or reduced at 43 a certain distance 25 back from its edges. As shown, the proportions and relations of the parts are such that when the cap edges 43 are just flush with the depressed cup edges 42, the springs are compressed to a proper maximum degree; while when the cap edges 43 get to be flush with the tops of the upstanding cup lugs 44 (between the cup depressions 42 and the cup slots 35), the springs will be so relaxed (through upward movement of the 30 wedge 20 due to wear at the box 16) as to require readjustment of the mechanism 25 by tightening up of the nut 27. Thus the member 30 which serves for turning the nut 27 and affords abutment for the springs 35 and 31 also cooperates with said nut to indicate quite plainly the state of adjustment of the mechanism 25 and of the wedge 20 at any time.

Referring, now, especially to Figs. 1, 2, 45 6 and 7, it will be seen that on the bottom of the member 30 are four equally spaced, low, radial, arc-shaped projections or protuberances 45, and that in the bottom of the bracket support 37 are corresponding shallow, 50 arc-shaped, radial depressions or recesses 46. By means of these projections 45 and depressions 46 at the abutting surfaces of the parts 30 and 37, the member 30 is held or locked against turning and thereby 55 loosening the nut 27, in consequence of vibration; also, overtightening of the nut 27 so as to compress the springs solid and so cause binding or jamming of the wedge 20 is effectually prevented. This latter result 60 follows from the fact that if the member 30 is turned down so as just to make the spring substantially solid, its projections 45 will rest on the flat surface of the support 37 so close to the depressions 46 that a slight 65 further turn will bring them into said depre-

sions and relax the spring; and the resistance to still further turning of the nut such as to carry the projections out of the depressions will then be so great that even the most careless workman will give up the attempt. 70 Leaving the projections 45 just about to enter a depression 46 with the springs solid, will, again, be harmless, because the pressure on the wedges 20 and 21 thus created will not be augmented sufficiently to cause 75 actual jamming by heating up and expansion of the parts in service before vibration will have caused the nut 27 to unscrew till the pressure is relaxed and the projections 45 drop into the adjacent depressions 46 that 80 they had last been turned past by the workman.

The mechanism 50 shown in Figs. 8 and 9 differs from the mechanism 25 of Figs. 1 to 7 in that the cup member 51 projects much 85 farther through the bracket support 52. As here shown, indeed, the support 52 is in effect a mere horizontal bar with a slightly depressed middle portion and an opening therein a little larger than the body of the 90 cup 51, which has an external flange 53 at its upper end that bears on the bracket 52 and supports the cup therefrom. The support 52 is strengthened with longitudinal 95 ribs 55 on its lower side that merge in an annular rib or flange 56 about the cup opening. Here the projections 57 and depressions 58 that correspond to 45 and 46 in Figs. 1 to 7 are on the cup flange 53 and on the subjacent portion of the support 52 on 100 which the flange abuts. The reduced lower end 59 of the cup 51 is hexagonal instead of square. In this construction, when the lower edges of the lugs 36 on the nut are flush with the bottoms of the recesses 35, 105 full adjustment of the wedge is indicated; but when the lower edges of the lugs have moved up to a position in line with the bottom of the bracket 52 at the point where reference character 56 is applied then the wedge 110 needs readjustment.

The construction shown in Figs. 10 and 11 differs from that just described in that the cup 61 has no reduced lower portion, but instead has a number of shallow longitudinal grooves 62 in its lower half that are adapted to receive projections on a spanner or other suitable tool,—so as to make it more difficult for unauthorized persons to tamper with the adjustment. 115

What we claim is:

1. Adjusting means for a compensating wedge comprising a wedge bolt, an adjusting nut thereon, and an actuating spring for the wedge acting through said nut, in 125 combination with a rotary member for producing relative rotation of bolt and nut affording abutment for said spring.

2. Adjusting means for a compensating wedge comprising a wedge bolt, an adjust- 130

- ing nut thereon, and an actuating spring for the wedge acting through said nut, in combination with a rotary member for producing relative rotation of bolt and nut affording abutment for said spring, and means for supporting said member, said member and said supporting means having mutually corresponding projections and depressions at their abutting surfaces.
10. Adjusting means for a compensating wedge comprising a wedge bolt, an adjusting nut thereon, and an actuating spring for the wedge acting through said nut, in combination with a member for turning the nut cooperating therewith to indicate the adjustment of the wedge.
15. Adjusting means for a compensating wedge comprising a wedge bolt, an adjusting nut thereon, and an actuating spring for the wedge acting through the nut, in combination with supporting means for said spring and a rotary member for producing relative rotation of bolt and nut projecting below said supporting means.
20. Adjusting means for a compensating wedge comprising a wedge bolt, an adjusting nut thereon, and an actuating spring for the wedge acting through the nut, in combination with a bracket and a rotary member for turning the nut affording abutment for said spring and projecting below said bracket.
25. Adjusting means for a compensating wedge comprising a wedge bolt, an adjusting nut thereon, and an actuating spring for the wedge acting through the nut, in combination with a bracket and a rotary member for producing relative rotation of bolt and nut affording abutment for said spring and bearing upon said bracket.
30. Adjusting means for a compensating wedge comprising a wedge bolt, an adjusting nut thereon, and an actuating spring for the wedge acting through the nut, in combination with a bracket and a rotary member for producing relative rotation of bolt and nut affording abutment for said spring and bearing upon said bracket.
35. Adjusting means for a compensating wedge comprising a wedge bolt, an adjusting nut thereon, and an actuating spring for the wedge acting through the nut, in combination with a bracket and a rotary member for producing relative rotation of bolt and nut affording abutment for said spring and bearing upon said bracket.
40. Adjusting means for a compensating wedge comprising a wedge bolt, an adjusting nut thereon, and an actuating spring for the wedge acting through the nut, in combination with a bracket and a rotary member for producing relative rotation of bolt and nut affording abutment for said spring and bearing upon said bracket.
45. Adjusting means for a compensating wedge comprising a wedge bolt, an adjusting nut thereon, and an actuating spring for the wedge acting through the nut, in combination with a bracket and a rotary member for producing relative rotation of bolt and nut to tighten the spring, and means for preventing overtightening on said spring.
50. An adjustable wedge structure comprising, in combination, a wedge bolt, a spring, a supporting bracket, a rotatable spring pocket having a shank projecting below the bracket and a nut on the bolt for adjusting the spring rotatable with the spring pocket.
55. Adjusting means for a compensating wedge comprising a wedge bolt, an adjusting nut thereon, an actuating spring for the wedge acting through said nut, supporting means for said spring, and a rotary member for producing relative rotation of bolt and nut affording abutment for the spring and cooperating with said supporting means to prevent overtightening on the spring.
60. Adjusting means for a compensating wedge comprising a wedge bolt, an adjusting nut thereon, an actuating spring for the wedge acting through said nut, and supporting means for said spring in free-sliding, anti-turning engagement with said nut.
65. Adjusting means for a compensating wedge comprising a wedge bolt, an adjusting nut thereon, an actuating spring for the wedge acting through said nut, and supporting means for said spring cooperating with said nut to indicate the adjustment of the wedge.
70. Adjusting means for a compensating wedge comprising a wedge bolt, an adjusting nut thereon, an actuating spring for the wedge acting through said nut, and supporting means for said spring in free-sliding, anti-turning engagement with said nut.
75. Adjusting means for a compensating wedge comprising a wedge bolt, an adjusting nut thereon, an actuating spring for the wedge acting through said nut, and supporting means for said spring cooperating with said nut to indicate the adjustment of the wedge.
80. In testimony whereof, we have hereunto signed our names.

WILLIAM E. WOODARD.
FREDERICK W. MARTIN.
